UNITED STATES PATENT OFFICE.

WILLIAM R. JENKINS, JR., OF BELLEFONTE, PENNSYLVANIA.

POWER-HAMMER.

SPECIFICATION forming part of Letters Patent No. 358,672, dated March 1, 1887.

Application filed February 23, 1886. Serial No. 152,921. (No model.)

To all whom it may concern:

Be it known that I, WILLIAM R. JENKINS, Jr., a citizen of the United States, residing at Bellefonte, in the county of Centre and State of Pennsylvania, have invented certain new and useful Improvements in Power-Hammers; and I do hereby declare the following to be a full, clear, and exact description of the invention, such as will enable others skilled in the art to which it appertains to make and use the same.

My invention relates particularly to that class of power-hammers wherein the hammer operates through an oscillating helve having proper bearings between the hammer and the mechanism for driving the same, and more especially is it designed as an improvement upon my former patent, No. 237,872, of February 15, 1881; and it consists in an improved construction and arrangement of the elastic cushions at the fulcrum of the helve, and in elastic cushions placed above and below the connection of the helve with the ram which carries the hammer, whereby the blow of the hammer is rendered more elastic and yielding and the helve relieved from any excessive shock, all as will be more fully hereinafter explained and understood.

For a more thorough understanding of the details of construction and arrangement attention is invited to the accompanying drawings, in which—

Figure 1 is a side elevation of my improved power-hammer; Fig. 2, a longitudinal section of the helve, the cushions, and the ram; and Fig. 3, a transverse section of the helve and its fulcrum.

Like letters denote corresponding parts in the several views.

The frame is made in two parts, A representing the lower part or base, which supports the anvil and driving mechanism, and A' the upper part, having vertical extensions B B', the said parts A A', comprising the frame, being bolted together, as shown, and furnishing a strong and substantial support for all the necessary parts. The extension B has the usual vertical guide, a, for the ram D to slide in, and said guide is secured by screws a', so as to be adjustable and removable to provide for the wearing of these parts. The exten-

sion B' of the upper part consists of two uprights, b b, and an upper and lower connecting cross-beam b' b', which latter pass through said uprights, and are secured by vertically arranged screw-bolts, b² b² and b³ b³, respectively. In this extension B' is fulcrumed the oscillating helve C, which passes through a bearing-block, C', secured thereto, and made with a recess or semi-cylindrical pocket, e, in its top and bottom, as shown in Figs. 2 and 3. This block has bearing both above and below against elastic cushions E E, which are seated in the recesses or pockets c c of said block and in corresponding recesses or pockets c' c' of the upper and lower cross-beams b' b'. These elastic cushions may be made of any suitable material and of any shape, but are preferably made of rubber and elliptical in shape, so as to more readily accede to the movement of the helve. The forward end of the helve C passes into a recess, d, made in the upper end of the ram D, which carries the hammer D', and elastic cushions F F, preferably round and of rubber, are placed above and below this end of the helve, and are each held in place both above and below by pockets or recesses d' d', similar to those at the fulcrum of the helve.

To the rear end of the helve is attached the lever G, which has connection with a crank-shaft, H, provided with a driving-pulley, H', and mounted in suitable bearings upon the base A of the frame; also, upon this base A, and near the driving-pulley, is pivoted a socket or sleeve, I, through which passes an adjustable arm, I', carrying on its upper end a stress-pulley, J, which has action upon the belt passing around the driving-pulley. This stress-pulley is for the purpose of regulating the force of the blow, and is operated by a treadle, K, with which it is connected by means of a rod, e, and arm f, the latter being properly connected to the socket or sleeve I. This treadle is pivoted to the base, as shown, and is supported by a leaf-spring, K', which forces it back to its normal position when the foot is removed. By using elastic cushions at the connection of the helve with the ram, the blow is rendered more elastic and yielding, and the helve is relieved from any excessive shock.

By the present arrangement of the elastic

cushions above and below the fulcrum of the helve, I dispense with the fulcrum-pins and rocker-arm used in my former patent, and bring the elastic bearings into closer contact 5 with the fulcrum, making the action of the helve more effective and rendering the cost of the hammer much less than formerly.

Having thus described my invention, what I claim, and desire to secure by Letters Patent, is—

1. A power-hammer with an oscillating helve pivotally connected at one end to the crank-shaft directly and elastically connected at the other end to the ram, and having an intermediate elastic fulcrum, substantially as described.
2. In a power-hammer, the combination of a ram moving in vertical guides and an oscillating helve with one end passing into and 20 connected to the ram between two elastic cushions, with the other end pivotally connected to the crank-shaft, and with an intermediate elastic fulcrum, substantially as described.
25. 3. A power-hammer having an oscillating

helve pivotally connected at one end to a crank-shaft and provided with elastic cushions directly above and below its fulcrum, and with elastic cushions directly above and below its connection with the ram, substantially as described.

4. A power-hammer having an oscillating helve provided with a recessed bearing-block at its fulcrum and elliptic elastic cushions placed above and below the fulcrum and set 35 in the recesses in said block and in similar recesses in the frame, substantially as described.

5. A power-hammer provided with an oscillating helve connected directly to the ram and having elastic ball-cushions placed above and below such connection, and held by recesses or pockets in the helve and in the ram, substantially as described.

In testimony whereof I affix my signature in presence of two witnesses.

WILLIAM R. JENKINS, JR.
